BOTTLE OR SIMILAR ARTICLE

Victor Koenigsberg, Franklin Square, N.Y., assignor to Colgate-Palmolive Company, New York, N.Y., a corporation of Delaware

Filed Mar. 4, 1965, Ser. No. 84,087

Term of patent 14 years

(Cl. D58—8)

FIG. 1

FIG. 3

FIG. 1 is a top plan view of a bottle or similar article, embodying my new design;

FIG. 2 is a side elevational view, the other side being substantially a mirror image thereof;

FIG. 3 is an end elevational view, the other end being substantially a mirror image thereof; and

FIG. 4 is a bottom plan view thereof.

I claim:

The ornamental design for a bottle or similar article, as shown and described.
